UNITED STATES PATENT OFFICE.

THOMAS M. BAINS, JR., OF PHILADELPHIA, PENNSYLVANIA, ASSIGNOR TO GENERAL ELECTRIC COMPANY, A CORPORATION OF NEW YORK.

VARIABLE-VOLTAGE TRANSFORMER.

No. 865,985.

Specification of Letters Patent.

Patented Sept. 17, 1907.

Application filed February 8, 1907. Serial No. 366,478.

To all whom it may concern:

Be it known that I, THOMAS M. BAINS, Jr., a citizen of the United States, residing at Philadelphia, county of Philadelphia, State of Pennsylvania, have invented 5 certain new and useful Improvements in Variable-Voltage Transformers, of which the following is a specification.

My invention relates to variable-voltage transformers of the type in which the primary flux is shifted into and 10 out of inductive relation to the secondary winding, so as to vary the induced secondary voltage.

The object of my invention is to provide a novel construction for such transformers, which is compact and of high efficiency.

15 In carrying out my invention, I arrange the core with three legs and mount the primary coil on one leg with the secondary coil surrounding both the leg on which the primary coil is placed, and also a second leg. And I provide a movable magnetic member for shifting the 20 primary flux from one to the other of the other two legs. Or, expressed in another way, I arrange the secondary coil outside of the primary coil with an inside diameter substantially greater than the outer diameter of the primary coil, and shift the primary flux from a return-path 25 within the secondary coil to a return path outside of it. When the flux returns through the secondary coil, it induces no voltage in it, but when it returns outside the secondary coil, the primary flux is interlinked with the secondary coil in the usual manner.

30 My invention further comprises employing an auxiliary secondary coil, so arranged as to oppose the induced secondary voltage, due to leakage, in the position of minimum voltage, so as to secure a resultant secondary voltage of zero. This coil is so arranged as 35 to be of practically no effect when the induced secondary voltage is at its maximum.

My invention will best be understood by reference to the accompanying drawings, in which

Figure 1 shows a side elevation in cross-section of a 40 variable voltage transformer arranged in accordance with my invention; Fig. 2 shows a plan view of the same; Fig. 3 shows the core and coils diagrammatically; and Fig. 4 shows a modification.

In the drawings, A represents a magnetic core, which 45 has three parallel legs a^1 , a^2 , and a^3 . On the central leg a^2 is mounted the primary coil B.

C is the secondary coil, which surrounds both the primary coil B and the leg a^1 . The secondary coil thus has an inside diameter substantially greater than 50 the outer diameter of the primary coil.

D represents a movable magnetic member which is supported from and slides on the rods E; being moved by a hand-wheel F, to which it is connected by a rack and pinion, as shown in Fig. 2. When the member D 55 is in the position shown in Figs. 1, 2 and 3, it forms a

nearly closed magnetic circuit with the legs a^1 and a^2 , so that the primary flux in the leg a^2 finds a return path through the leg a^1 . This return path is inside the secondary coil, and induces no voltage in the secondary coil, so that this position of the member D corresponds to minimum secondary voltage. When the member D is moved into the position shown in dotted lines in Fig. 3, a nearly closed magnetic circuit is formed with the legs a^2 and a^3 . The primary flux now returns outside the secondary coil C, and is consequently linked with this coil in the usual manner. The dotted line position of member D is consequently the position of maximum induced secondary voltage. At intermediate positions the induced voltage will have intermediate value.

If it were not for leakage, the induced secondary voltage would be zero, with the arrangement of windings shown in Fig. 3, when the member D is in its full-line position. A certain portion of the primary flux, however, will leak across to the leg a^1 , and consequently return outside of the secondary coil. This leakage flux is interlinked with the secondary coil and induces a certain voltage therein. In order that the minimum value of the secondary voltage may be zero, I make use of the auxiliary secondary winding c, shown in Fig. 4. I place this winding on the leg a^1 and connect it in opposition to the main secondary winding C. When the member D is in the position of minimum induced secondary voltage, which is the dotted-line position in Fig. 4, the greater part of the primary flux is linked with the auxiliary winding c and induces therein a voltage which neutralizes the voltage induced in the main secondary winding C by the leakage flux, so that the resultant secondary voltage is zero. When the member D is in the full-line position in Fig. 4, in which the induced secondary voltage is maximum, the auxiliary secondary winding c is threaded only by a small leakage flux, and consequently has a practically negligible effect.

I do not desire to limit myself to the particular construction and arrangement of parts here shown, but aim 95 in the appended claims to cover all modifications which are within the scope of my invention.

What I claim as new and desire to secure by Letters Patent of the United States, is,—

1. In a variable voltage transformer, a three-legged core, a primary winding surrounding one leg, a secondary winding surrounding both the leg carrying the primary winding and a second leg, and means for directing the flux from the leg carrying the primary winding through the other two legs alternately.

2. In a variable voltage transformer, a three-legged core, a primary winding surrounding one leg, a secondary winding surrounding both the leg carrying the primary winding and a second leg, and means for gradually shifting the return flux of the primary winding from one to the other of the other two legs.

3. In a variable voltage transformer, a three-legged

core, a primary winding surrounding one leg, a secondary winding surrounding both the leg carrying the primary winding and a second leg, and a movable magnetic member adapted to form a nearly closed magnetic circuit with the 5 leg carrying the primary winding and either of the other legs.

4. In a variable voltage transformer, a primary coil, a secondary coil surrounding the primary and having an inside diameter substantially greater than the outside diameter of the primary coil, and means for causing the 10 flux passing through the primary coil to return either inside or outside the secondary coil.

5. In a variable voltage transformer, a primary coil, a secondary coil surrounding the primary and having an 15 inside diameter substantially greater than the outside diameter of the primary coil, and a movable magnetic member adapted gradually to shift the flux passing through the primary coil from a return path inside the secondary coil to a return path outside it.

20 6. In a variable voltage transformer, a three-legged core, a primary winding surrounding one leg, a main secondary winding surrounding both the leg carrying the

primary winding and a secondary leg, means for directing the flux from the leg carrying the primary winding through the other two legs alternately, and an auxiliary 25 secondary winding opposing the main secondary winding and carried on the leg surrounded by the main secondary and not by the primary winding.

7. In a variable voltage transformer, a primary coil, a main secondary coil surrounding the primary and having an inside diameter substantially greater than the outside 30 diameter of the primary coil, a movable magnetic member adapted gradually to shift the flux passing through the primary coil from a return path inside the main secondary coil to a return path outside it, and an auxiliary secondary coil in inductive relation to the return path within the main secondary coil and connected in opposition to the main secondary coil. 35

In witness whereof, I have hereunto set my hand this 25th day of January, 1907.

THOMAS M. BAINS, JR.
